Attorney.

UNITED STATES PATENT OFFICE.

FRANK J. LEMIEUX, OF PAWTUCKET, RHODE ISLAND.

PUMP PISTON.

Application filed September 28, 1923. Serial No. 665,365.

To all whom it may concern:

Be it known that I, FRANK J. LEMIEUX, a citizen of the United States of America, residing at Pawtucket, in the county of Providence and State of Rhode Island, have invented certain new and useful Improvements in Pump Pistons, of which the following is a specification.

This invention relates to improvements in pistons for use in pumps employed for forcing molten type metal into molds adapted for forming type.

In monotype, linotype, intertype, liner-type and linergraph machines, wherein molten metal is handled for forming type, it is the general practice to employ a structure which includes a melting pot with a pump cylinder properly positioned to receive the molten metal from the pot for forcibly feeding the same to the type molds. Such pump cylinders, for practical purposes, are provided with small bores approximately seven-eighths of an inch to two inches in diameter and are usually equipped with solid plug 20 pistons which speedily wear out. It is, therefore, necessary to replace the entire piston every time it becomes so worn that it no longer fits the cylinder bore.

It is very obvious that the solid plug pistons now in use should be replaced by piston heads carrying split packing rings. The difficulty encountered in employing packing rings, however, is that they are necessarily of very small diameter and consequently 35 very heavy and stiff. It is, therefore, almost impossible to insert these split rings into their respective grooves, over the piston head, without breaking.

In the monotype, or single type casting, machines, these solid plug pistons are usually provided with a port or passageway through which the molten metal is allowed to pass to reach the portion of the pump cylinder in advance of the piston head. The 45 diameter of this port or passageway naturally regulates the amount of molten metal fed into the cylinder during each stroke of the piston, which amount should be maintained constant. The passage of molten metal 50 through the port or passageway, however, has a tendency to enlarge the same with the result that too much metal is fed into the cylinder after the piston head has been in use for a time. This condition, also, neces-

sitates the replacing of the entire piston 55 head.

It is, therefore, an important object of this invention to provide a piston head which may be disassembled for permitting packing rings to be placed in their respective 60 grooves without danger of breaking.

A further object of the invention is to provide a piston head which is formed from a plurality of parts with a molten metal feeding port or passageway formed entirely 65 within one part so that the latter may be replaced, when the port or passageway becomes too large to efficiently perform its desired function, without necessitating the replacing of the entire piston head. 70

Other objects and advantages of the invention will be apparent during the course of the following description.

In the accompanying drawing forming a part of this specification and in which like numerals are employed to designate like parts throughout the same,

Figure 1 is an elevational view of a fragmentary portion of a piston embodying this invention,

Figure 2 is a detail elevational view of a removable end portion which forms a part of the piston head shown in Fig. 1,

Figure 3 is an end plan view of the removable end portion shown in Fig. 2,

Figure 4 is a detail elevational view of a removable spacer ring which forms a part of the piston embodying this invention,

Figure 5 is a partly elevational view and partly sectional view of the piston embodying this invention taken upon lines V—V of Fig. 1,

Figure 6 is a transverse sectional view taken upon line VI—VI of Fig. 5.

Figure 7 is a transverse sectional view 95 taken upon line VII—VII of Fig. 5, and

Figure 8 is a partly elevational and partly sectional view of a modified form of piston embodying this invention.

Referring to the drawings and particularly to Figures 1 to 7 inclusive, the numeral 10 designates a fragmentary portion of a piston rod having an enlarged end portion 11 which is formed with a reduced ring receiving extension 12 forming a shoulder 100 portion 13, as illustrated. This enlarged end portion is provided with an axially arranged threaded bore 14 which is adapted for re-

ceiving the externally screw threaded stud 15 carried by the removable spacer ring 16 which is employed for retaining the upper split packing ring 17 in position within the 5 ring receiving portion formed in the enlarged end portion 11 by the extension 12. This removable spacer ring 16 is provided with a reduced ring receiving extension 18 which is provided with an internally screw 10 threaded recess 19 that is adapted for receiving the externally screw threaded boss 20 formed on the removable end portion 21. This removable end portion is provided with an annular groove 22 formed in its side wall 15 which communicates with the transversely extending portion 23 of a port or passageway formed in the removable end portion 21. This transversely extending passageway portion 23 communicates at its inner end 20 with an axially extending portion 24 of the port or passageway which terminates at its outer end at the outer face of the removable end portion 21. This end portion 21 is further provided with a reduced extension 25 25 which may be formed with a knurled surface or of square formation for the purpose of receiving a wrench to facilitate connecting the end portion 21 and the removable spacer ring 16 to the piston rod 10. A second split packing ring 17^a is positioned within the ring receiving portion formed in the spacer ring 16 and is retained in its proper position by the removable end portion 21.

In assembling the piston construction just 35 described, the split packing ring 17 is first positioned upon the rod 10 after which the removable spacer ring 16 is secured to the said rod. The second split packing ring 17^a is then positioned upon the spacer ring 16 40 and the end portion 21 is then attached to the spacer ring.

In the type of piston shown in Figure 8, there is provided a piston rod 26 having a tapered socket 27, of square formation in 45 transverse section, formed therein. An enlarged end portion 28 having a tapered shank 29, of similar formation to the socket 27, is adapted to be removably secured to the end of the piston rod by inserting the said 50 shank into the socket and locking the same therein by a transversely extending pin 30. The enlarged end portion 28 is provided with a packing ring receiving portion 31 and an internally screw threaded bore 32. 55 The split packing ring 33 is receivable in the portion 31 while the bore 32 is adapted for receiving the threaded stud 34 carried by a spacer ring 35. This spacer ring 35 is 60 similarly formed to the spacer ring 16, shown in Figs. 1 and 4 to 6 inclusive, and is adapted for receiving the split packing ring 33^a in the manner illustrated. The end portion 36 is removably connected to the 65 spacer ring 35 by the same construction illustrated and described in connection with

the removable end portion 21 forming a part of the piston head shown in Figs. 1 to 7 inclusive. This removable end portion 36 is not provided, however, with a port or passageway.

It will be apparent, to those skilled in the art, that the type of piston shown in Fig. 8 is especially adapted for use in slug casting machines. The manner of assembling this piston head is identical with that 75 of the head previously described with the exception that the enlarged end portion 28 may be removed from the piston rod 26 by withdrawing the transverse pin 30.

It will be seen that these piston structures permit the placing of split packing rings of very small diameter upon a piston head and for replacing the portion of a head which has formed therein a molten metal feeding port or passageway.

It is to be understood that the forms of this invention herewith shown and described are to be taken as the preferred examples of the same, and that various changes 85 in the shape, size, and arrangement of parts 90 may be resorted to without departing from the spirit of the invention or the scope of the subjoined claims.

Having thus described the invention, I 95 claim:

1. A piston of a type adapted for permitting a predetermined amount of molten metal to pass therethrough during its reciprocating movement within a cylinder, 100 said piston comprising a piston rod, and a piston head formed of a plurality of separate parts detachably secured to said rod, one of said detachable parts having a passageway therethrough adapted for permitting the flow of metal through said head.

2. A piston of a type adapted for permitting a predetermined amount of molten metal to pass therethrough during its reciprocating movement within a cylinder, 110 said piston comprising a piston rod, a ring receiving portion formed on said rod, a spacer ring detachably secured to said rod, a ring receiving portion formed thereon, and a removable end portion secured to the spacer ring having a passageway therethrough adapted for permitting the flow of metal through said head.

3. In a piston of the type described, a piston rod having an enlarged end portion, a packing ring receiving portion formed in said end, a spacer ring removably secured to the enlarged end portion, a packing ring receiving portion formed in the spacer ring, and a removable end portion secured to the spacer ring, said spacer ring and end portion being adapted for being removed to permit the placing of packing rings in their proper places, said removable end portion having a passageway therethrough for permitting a flow of molten metal through 130

the head during its reciprocating movement within a cylinder, said end portion being replaceable when said passageway becomes worn out.

4. In a piston of the type described, a piston rod carrying an enlarged end portion, a packing ring receiving portion formed in said end, a packing ring in said portion, a spacer ring having a packing

ring receiving portion removably secured to 10 said enlarged end portion, a packing ring in said portion, an end portion, and means for removably connecting said end portion to said spacer ring.

In testimony whereof I affix my signature. 15

FRANK J. LEMIEUX.
